DESIGN FOR A GAME BOARD

Ernest A. Villeneuve, Woonsocket, R. I.

Application November 25, 1940, Serial No. 96,798

Term of patent 7 years

To all whom it may concern:

Be it known that I, Ernest A. Villeneuve, a citizen of the United States, residing at Woonsocket, in the county of Providence and State of Rhode Island, have invented a new, original, and ornamental Design for a Game Board, of which the following is a specification; reference being had to the accompanying drawing, forming a part thereof.

The figure is a plan view of a game board, showing my new design.

The board is of no appreciable or substantial thickness.

I claim:

The ornamental design for a game board, as shown and described.

ERNEST A. VILLENEUVE.
